(57) **CLAIM**

I claim the ornamental design for a plateholder, as shown and described.

DESCRIPTION

FIG. 1 is a left-side perspective view of a plateholder incorporating my design.

FIG. 2 is a right-side perspective view thereof.

FIG. 3 is a rear view thereof.

FIG. 4 is a right side view thereof.

FIG. 5 is a left side view thereof.

FIG. 6 is a front view thereof.

FIG. 7 is a top view thereof; and,

FIG. 8 is a bottom view thereof.

The broken lines shown in the figures are for the purpose of illustrating portions of the plateholder and form no part of the claimed design.
